Bright & Bros.

UNITED STATES PATENT OFFICE.

JAMES W. KNOBLOCK, OF NEW YORK, N. Y., ASSIGNOR TO AMERICAN LA FRANCE FIRE ENGINE CO., INC., OF ELMIRA, NEW YORK, A CORPORATION OF NEW YORK.

FOCUSING DEVICE FOR PROJECTORS.

1,341,472.

Specification of Letters Patent.

Patented May 25, 1920.

Original application filed June 19, 1917, Serial No. 175,626. Divided and this application filed March 22, 1918. Serial No. 223,963.

To all whom it may concern:

Be it known that I, JAMES W. KNOBLOCK, a citizen of the United States, residing in New York, in the county of New York and 5 State of New York, have invented certain new and useful Improvements in Focusing Devices for Projectors, of which the following is a full and clear specification.

This case, which is a division of my 10 original application, Serial No. 175,626, filed June 19th, 1917, for improvements in electric hand lanterns, covers a novel device for supporting and focusing an electric light bulb with reference to the reflector of an 15 electric lamp. The invention is illustrated and described with particular reference to an electric lantern because that is the form in which it is illustrated in the above named original application, but it will be understood that the invention is of broader 20 application and may be used in various forms of electrically illuminated projectors, lamps, etc.

In order that the invention may be fully 25 understood I will first describe the same with reference to the accompanying drawing and afterward point out the novelty more particularly in the annexed claims.

The accompanying drawing illustrates a 30 vertical longitudinal sectional view of an electric hand lantern having the present invention applied thereto.

1 is a sheet metal casing or container of general rectangular configuration formed 35 with a reinforced bottom 2, a removable cover 3 for the open top, a vertically elongated central depression or recess 4 in the back wall, and a circular inwardly flanged rim 5 projecting slightly from the front 40 wall to form a support for the lamp reflector and the protecting lens or front glass.

20 is the ordinary concave reflector formed with an annular flange which is presented within the inwardly flanged rim 5, to which 45 it is rigidly secured by rivets or screws and nuts. Since the flanged rim 5 projects over the edge of the reflector 20, it will be understood that an effective spray proof joint between the two is obtained.

50 The reflector 20 is provided, as usual, with a central socket or opening 20^a in which is mounted a flanged collar 45, carrying a set screw which engages a second collar 47, mounted concentrically within the collar 45,

and projecting rearwardly and formed at 55 its inner end with a slightly contracted throat 48, in which is mounted a cylindrical lamp socket 50 containing the usual internal arrangement of contacts and wires. The socket 50 is formed with bayonet joint slots 60 51, with which engage the oppositely projecting radial pins or screws 52, projecting from the base of the electric bulb 53.

The lamp supporting socket 50 is freely fulcrumed in the contracted throat 48 and 65 has ample clearance in the forward end of supporting collar 47, so that it can rock freely up or down or sidewise or at any angle from the center line of the reflector, in order to centralize the lamp filament with 70 reference to the reflector. The socket member 50 has secured to it a wire key 50^a which operates freely in an enlarged key-way 48^a in the contracted throat of collar 47 so as to prevent the rotation of socket 50 within 75 collar 47 and at the same time permit sufficient freedom of movement for the purpose explained. This mounting of the lamp socket also permits the adjustment of the lamp either forward or backward within the 80 reflector to obtain a proper focus in the reflector, for making either a concentrated beam of light or a wider spread of light, as may be desired.

55 is a yoke or cup-shaped member open 85 at the top to permit the entrance of circuit wires to the socket 50 and closely engaging and frictionally connecting with the rear end of the socket 50. This member 55 is rigidly mounted upon the inner end of a 90 screw stem 56, threaded through a sleeve 57 provided at its outer end with a knurled head 58 and at its inner end with a collar 59, confining a spring washer 59^a against the head 61 to frictionally hold sleeve 57 in 95 position. The sleeve 57 rotates freely in a concentric sleeve 60, rigidly connected with the inner head 61, engaging the inner concave face of the inset plate 62 (hereinafter referred to) the sleeve 60 passing through 100 the enlarged opening 63 of plate 62 and carrying at its outer end the milled clamping nut 64, which engages the outer convex face of plate 62 and the lock nut 65, which engages the nut 64. Nuts 64 and 65 are 105 threaded upon the sleeve 60.

The inset plate 62 is secured upon the inner face of the wall of depression 4 of

the lamp casing, above referred to. This depression 4 has an opening 4^a cut through its inner wall and the inset plate 62 has a shallow dished or spheroidal portion 62^a, which rests in the cut out 4^a directly behind the central axis of reflector 20. This inset plate 62 is secured to the metal casing by means of set screws shown at 67.

From the described construction of adjustable bulb supporting devices it will be understood that by loosening the nuts 64 and 65 the screw stud 56 can be shifted up or down or sidewise or at any angle in the lamp casing, carrying with it the lamp socket 50 and bulb 53, the socket being fulcrumed in the throat of the collar 47. When the bulb is properly centralized in the reflector 20, the nuts 64 and 65 are tightened to retain this adjustment. Then by means of the knurled head 58 the sleeve 57 can be rotated to move the screw stem 56 and connected socket 50 inwardly or outwardly to get the desired focus.

No attempt has been made to illustrate the electrical connections between the source of electricity and the lamp supporting socket 50 nor the controlling switch. These may be arranged as shown in my above named original application of which this is a division, or they may be differently arranged depending upon the application of the invention, since these devices are outside of the scope of the present invention.

The adjustable mechanism for supporting

the lamp bulb enables the adjustment of 35 the bulb while the lamp is burning and by means of such adjustment the desired result can be obtained for the various uses, for which the lamp is suitable.

I claim:

1. In a device of the character described, the combination of a suitable casing, a reflector secured in the front wall of said casing, a collar secured to the rear of said reflector, a bulb supporting socket adjustably mounted in said collar, a rotatable threaded sleeve projecting through an enlarged opening in the rear wall of said casing, and adjustable transversely therein, a threaded stem screwed into said sleeve and connected 45 with said bulb supporting socket, means for adjusting said sleeve at an angle to the axis of the reflector, and means for rotating said sleeve to adjust said stem therein.

2. In a device of the character described, the combination of a suitable casing, a reflector secured therein, a bulb supporting socket adjustably mounted upon said reflector, a portion of the rear wall of said casing formed with a spheroidal recess having an opening through it, a threaded sleeve, carrying a clamping nut, extending through said rear wall opening and adjustable therein at any angle transversely of the axis of the reflector, a threaded stem suitably connected with the bulb supporting socket and adjustably mounted in said threaded sleeve.

JAS. W. KNOBLOCK.
